PUMP

James A. Armitage, Houston, Tex.

Application April 20, 1934, Serial No. 721,520

7 Claims. (Cl. 103—239)

This invention relates to a pump and has particular relation to that type of pump whereby liquid may be elevated by the application of motive fluid, under pressure thereto.

5 An object of the invention is to provide a pump specially adapted for use in wells, and similar places, and by the use of which an operating fluid, under pressure may be applied to the liquid being elevated simultaneously in stages at spaced 10 intervals from the point of intake to the point of discharge.

Another object of the invention is to provide a pump embodying series of eduction tubes, having collecting chambers incorporated therein and 15 spaced apart the required distance, and pressure lines for delivering an operating fluid, under pressure, to said chambers and in such concert that the pumped liquid will be elevated in stages, or loads, from chamber to chamber.

20 A further object is to provide, in a pump, a novel type of collecting chamber for receiving the pumped liquid from beneath and entrapping the same, each chamber being provided with a float, forming a separator to exclude the operating 25 fluid from the eduction tubes and to exclude the pumped liquid from the pressure lines.

A still further object is to provide a pump embodying series of eduction tubes, collecting chambers incorporated therein, and fluid pressure lines arranged to apply an operating fluid under pressure to, and to relieve the fluid pressure from, said chambers in such concert that the pumped liquid will be elevated in isolated 30 loads, or stages, and the operating fluid will be applied, simultaneously, to the stages, or loads, being elevated.

The invention also comprehends a novel method of elevating liquid.

40 With the above and other objects in view this invention has particular relation to certain novel features of construction, operation and arrangement of parts an example of which is given in this specification, and illustrated in the accompanying drawings, wherein:—

45 Figure 1 shows a side elevation of the pump as assembled in a well.

Figure 2 shows a fragmentary side view taken at right angles to the view shown in Figure 1.

50 Figure 3 shows a side view of the control valve actuating mechanism.

Figure 4 shows a cross sectional view of one of the control valves.

55 Figure 5 shows a horizontal sectional view taken on the line 5—5 of Figure 8.

Figure 6 shows a similar view taken on the line 6—6 of Figure 7.

Figure 7 shows a vertical sectional view of the lower end of the pump.

Figure 8 shows a side elevation of an intermediate portion of the pump, shown partly in section, and Figure 9 shows a diagrammatic view.

Referring now more particularly to the drawings, wherein like numerals of reference designate similar parts in each of the figures the numerals 1, 1' designate the respective series of eduction tubes which are arranged alongside and which extend down into the well. These tubes connect, at their upper ends, into the U-connection 2 from which leads the discharge line 3.

For supplying operating fluid, under pressure, the lines 4, 4' are provided which lead down into the well alongside the eduction tubes.

Incorporated into these lines 4, 4' are the three way control valve mechanisms 5, 5' shown in detail in Figure 4.

Each control valve mechanism comprises a casting 6 having a rotary valve 7 therein, said valves having the stems 8, 8'. There are the pressure supply and the relief lines 9, 9'. The pressure supply line has the branches 10, 10' leading therefrom into the corresponding valve casings, and leading from said valve casings are the relief branches 11, 11' which enter the relief line 9.

Each valve 7 has the cross channels 12, 13 therethrough which merge, as shown in Figure 4, into a common channel 14. This channel 14 is in constant communication with the corresponding pressure line 4, or 4'. While the valve is in one position, the channel 12 communicates with the supply branch 10 or 10' and the channel 13 is closed and while in another position the channel 13 communicates with the relief branch 11 or 11' and the channel 12 is closed. It is to be noted that the channels 12, 13 of the valve mechanisms 5, 5' are reversed, that is, while the supply line 9 is in communication with one of the pressure lines it is closed to the other pressure line and said other pressure line is in communication with said relief line 9, and vice versa.

The valve stems 8, 8' have the shift arms 15, 15' fixed thereto and pivotally connected to these arms is the shaft bar 16. A shift lever 17 is pivoted at an intermediate point to a suitable support and one end of this lever is pivoted to the shift bar 16. The other end of the lever 17 has a slideable pivotal connection with one end of a push bar 18, which is slideable in the bearing 19 and the other end of the push bar has a roller 20 thereon. A cam wheel 21 is mounted to rotate

and is driven from a suitable power. This wheel has the spaced cams 22 thereon which successively contact with the roller 20 and impart successive thrusts to the push bar 18 and to the shift bar 16 in one direction in an obvious manner. A pull spring 23 is attached at one end to a fixed anchor and at its other end to the bar 16. This spring acts to impart successive thrusts to the bar 16 in the other direction, all to the end that 5 the valve 7 will be shifted back and forth to apply pressure to one pressure line and to simultaneously relieve the pressure from the other pressure line; and also provision may be made to create a suction to each line when so relieved. It is to be 10 understood that any type of valves, for controlling said pressure lines, suitable for the purpose may be used, and any type of controlling mechanism suitable for shifting said valves may be 15 employed, the particular types shown being for 20 the purpose of illustration.

At the lower ends of the lower eduction tubes of the series there are the inlet chambers 24, 24', which are enclosed by complementary casings 25, 25' suitably anchored together as a unit. These 25 chambers will be submerged in the liquid to be pumped from the well or reservoir. The chambers have the inlets 26, 26' which are shielded by the screens 27, 27' and are controlled by the inwardly opening flap valves 28, 28'. It is to be 30 understood that the castings and chambers therein and the means for controlling the inflow of liquid, as shown, are illustrative only.

The lower eduction tubes of the series 1, 1' 35 are connected into the respective chambers 24, 24'.

Spaced apart along the pump, preferably a uniform distance, are the elevating units designated generally by the numerals 29. Each unit, as shown, is composed of complementary castings secured together, each unit having the collecting chambers 30, 30', into which the corresponding pressure lines 4', 4, respectively, are connected, and also having the discharge passageways 31, 31'.

Beneath the collecting chambers and controlling 45 the corresponding series of eduction tubes are the upwardly opening valves, as 32, and controlling the inlet of liquid into the respective discharge passageways are the upwardly opening valves, as 33. In each collecting chamber there 50 is a float, as 34, and leading out from the side of each collecting chamber at its lower end and into the corresponding discharge passageway there is a by-pass channel 35. The pumped liquid entering a collecting chamber will elevate 55 the corresponding float, while the pressure thereabove is relieved; and upon the application of the operating fluid, under pressure, to said liquid in said chamber the liquid will be driven downwardly, the valve 32 beneath closing and the 60 liquid beneath the float will be forced out through the channel 35 up past the valve 33 and on up the corresponding eduction tube. In its upper position the float will close the inlet opening 36 of the corresponding chamber to prevent the 65 passage of pumped liquid into the corresponding pressure line, and in its lower position, the float will be forced over closely against, and will block, the inlet end of the by-pass 35 and prevent the operating fluid from entering the corresponding 70 eduction tube.

It will be observed that there are the two series of collecting chambers, those of one series being designated by the numerals 30 and those of the other series being designated by the numerals 75 30'. Any desired number of elevating units 29

containing these chambers may be employed and they may be spaced any selected distance apart, all in accordance with the requirements of the situation.

The pressure line 4 is connected into the collecting chambers 30', through the ports, as 36, thereof and above the respective floats and the pressure line 4' is similarly connected into the chambers 30.

As the pump is assembled and let down into the well one series of collecting chambers, as 30, may be primed, that is may be filled with liquid, the floats rising to the top of the chambers. The pump is lowered a sufficient distance, at least, to submerge the inlet chambers 24, 24' and the lower collecting chambers. The operating fluid under pressure, may then be applied to the floats of said chambers 30, through the pressure line 4', and simultaneously the line 4 will be relieved, or a suction created through it by any suitable 20 source of suction connected with the relief line 9'.

The liquid in chambers 30 will be thereby expelled into the corresponding eduction tubes 1' and will pass thence into the corresponding chambers 30' above. The lower chamber 30 will fill 25 by gravity from the corresponding inlet chamber 24. Pressure is then relieved from the pressure line 4' and applied through the line 4 to the collecting chambers 30' and the liquid expelled therefrom, as before, into the chambers 30 above.

During the normal operation of the pump the series of collecting chambers 30, 30' will be alternately filled and emptied. As a series of said chambers is emptied the liquid in the top chamber will be discharged out through the discharge line 3 and the bottom chamber of the emptied series will fill, by gravity, from the well. The loads from a series, as emptied, will be also elevated, or advanced, by stages or steps from the point of 40 intake to the point of discharge. It is to be noted that operating fluid is at all times excluded from the producing formation.

The pump may be lowered into the well and located at any desired point therein by means of 45 the cable 37 which is connected to be manipulated by any means at the ground surface suitable for the purpose. As will be noted by an inspection of Figures 7 and 8, the ports 36 of each series of collection chambers are enlarged downwardly, that is, the port of one chamber is slightly larger than the port of the next succeeding chamber above, so that when the operating fluid is applied the pressure exerted on the liquid in a series of chambers will be exerted approximately 55 simultaneously and equally from the upper to the lower chamber, to the end that the fluid will be discharged from all of the chambers of the series at the same time.

A preferred form of the construction and the 60 principle of operation have been disclosed by way of illustration only, but it is obvious that various mechanical changes may be made without departing from the principle of the invention and I reserve the right to make such changes 65 within the scope of the appended claims.

What I claim is:

1. Apparatus for elevating liquid comprising two series of liquid entrapping means adapted to be located in a well each having a chamber, said 70 chambers having ports the entrapping means of the respective series being spaced apart one above the other, conduits connecting the chambers of each series with chambers of the other series at higher elevations, the port of each chamber be- 75

ing slightly larger than that of the next succeeding chamber above, means including floats for applying an operating fluid, under substantially equal pressures, to the liquid in either 5 series of chambers simultaneously to effect such elevation of the liquid, and means for preventing the back flow of the liquid being pumped.

2. Apparatus for elevating liquid from a reservoir to a higher level comprising intake means 10 adapted to be submerged in the liquid of the reservoir and having chambers, series of collectors arranged one above the other and having collecting chambers, and a discharge outlet, the lower chambers of the series being connected into 15 the intake chambers, means through which the liquid in the collecting chambers may be simultaneously elevated in separate loads from the collecting chambers of one series to the collecting chambers of the other series, in alternate 20 succession, from intake to discharge, and means including floats for simultaneously applying an operating fluid, under equal pressures to the liquid in the chambers of one series and relieving said pressure from the chambers of the other 25 series, in alternate succession to effect the elevation of the liquid said chambers having ports, the ports of one chamber being larger than the ports of the next succeeding chamber above.

3. Apparatus for elevating liquid from a well 30 comprising series of entrapping means, the entrapping means of each series being spaced apart one above the other and formed to entrap loads of liquid, said apparatus having a discharge outlet and two series of conduits through which the 35 entrapped loads may be elevated from the entrapping means of one series to the entrapping means of the other series, alternatively.

4. Apparatus for elevating liquid from a well comprising series of entrapping means, the entrapping means of each series being spaced apart 40 one above the other and formed to entrap loads of liquid, said apparatus having a discharge outlet and two series of conduits through which the entrapped loads may be elevated from the entrapping means of one series to the entrapping 45 means of the other series, alternatively, and means preventing the back flow of liquid through said conduits.

5. Apparatus for elevating liquid from a well comprising series of entrapping means, the entrapping means of each series being spaced apart one above the other and formed to entrap loads of liquid, said apparatus having a discharge 5 outlet and two series of eduction conduits through which the entrapped loads may be elevated from the entrapping means of one series to the entrapping means of the other series, alternatively, means through which an operating fluid may be 10 applied, under pressure, to the entrapped liquid of one series and simultaneously relieved from the entrapped liquid of the other series in alternative succession.

6. In apparatus shaped to be inserted in a well 15 and adapted to elevate liquid, a liquid entrapping means having a collecting chamber provided with an inlet and a side outlet, a back pressure valve controlling the inlet, an eduction tube leading from the outlet, means preventing the 20 back flow of the liquid in the tube, said apparatus having a conduit for operating fluid entering the chamber above the entrapped load and a float in the chamber excluding the pumped liquid from said conduit and also movable under pressure 25 to exclude the operating fluid from the eduction tube.

7. In apparatus of the character described shaped to be inserted into a well and adapted to elevate liquid, a liquid entrapping means having a collecting chamber provided with an inlet and a side outlet, a back pressure valve controlling the inlet, an eduction tube leading from the outlet, means preventing the back flow of the liquid in the tube, said apparatus having a conduit for operating fluid entering the chamber 30 above the entrapped load and a float fitted in the chamber and arranged to be forced downwardly by the operating fluid against the entrapped load to expel said load, and upon the 35 expulsion of the load being movable under the influence of the pressure of the operating fluid into position to close the side outlet to exclude the pumped liquid from the conduit and to also exclude the operating fluid from the eduction 40 tube.

JAMES A. ARMITAGE.
